UNITED STATES PATENT OFFICE

2,556,395

EXPANSIBLE BIT SCREW DRIVER

Charles O. MacLean, East Greenwich, R. I.

Application December 19, 1947, Serial No. 792,692

3 Claims. (Cl. 145—50)

1

This invention relates to new and useful improvements in screw-drivers and the primary object of the present invention is to provide a screw-driver including a pair of spreadable companion jaws insertable in the kerf of a fastener, and embodying novel and improved means for selectively spreading said jaws to frictionally engage or wedge in the kerf of a fastener.

Another important object of the present invention is to provide a screw-driver so designed as to facilitate the same to frictionally support fasteners in such a manner as to facilitate fasteners to be installed in machinery, electrical apparatus, and the like, where a user's hand would usually be restricted and difficult to extend.

A further object of the present invention is to provide an expandable jaw screw-driver including means for spreading the jaws of said screw driver and novel and improved means for actuating said jaw spreading means in a selected locked position.

A still further aim of the present invention is to provide an expandable jaw screw-driver that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present expandable jaw screw-driver;

Figure 2 is an enlarged longitudinal vertical sectional view taken substantially through the center of Figure 1, and with parts thereof broken away and shown in section;

Figure 3 is a transverse horizontal sectional view taken substantially on the plane of section line 3—3 of Figure 2;

Figure 4 is a perspective view of the jaw actuating member used in conjunction with the present invention;

Figure 5 is a group perspective view of the gripping jaws used in conjunction with the present invention, and showing the same disassembled; and

Figure 6 is a fragmentary side elevational view of the lower end of the present tool, showing the same in use, and with parts broken away and shown in section.

Referring now to the drawings in detail, where-

2

in for the purpose of illustration, there is disclosed a preferred embodiment of the present invention, the numeral 10 represents a tubular body or shank having an open lower end 12 and a preferably open upper end 14. The upper end 14 is suitably fixed in an annular recess 16 provided in the lower end of a suitable handle 18 having a longitudinal bore 20 in which there is rotatably and slidably mounted the outer end 22 of an adjustable rod or shaft 24. This shaft 24 is provided with an enlarged externally threaded central portion 26 that receivably engages internal threads 28 projecting from the inner periphery of the body 10. The outer extremity 30 of the shaft 24 is provided with a transverse opening or slot 32 that aligns a diametrical bore 34 provided in a finger receiving plate 36. A pin 38 frictionally positioned in the slot 32 and bore 34 retains the plate positioned relative to the shaft 24. Rigidly secured to the lower or inner extremity 40 of the shaft 24, is the upper closed end 42 of a sleeve-like piston 44 that is workable within the shank 10.

The numerals 46 and 48 represent a pair of companion jaws generally, having opposed bearing faces 50 and 52 that normally frictionally engage each other. One of the jaws, for example jaw 48, is provided with a pair of outwardly projecting, spaced pivot ears 54 that extend outwardly from the face 52 of said jaw to loosely engage recesses 56 provided in the other of said jaws, namely, jaw 46.

Pivotedly securing the ears 54 in the recesses 56, is a pivot pin 58, the ends 60 and 62 of which pivotally engage apertures 64 and 66 provided in the shank 10, adjacent its lower end 12. It should be noted, that one of these apertures, for example aperture 64, terminates in an arcuate slot 66a that communicates with a longitudinal slot 68 provided in the end 12 of the shank, whereby the pin and jaws may be disengaged from the shank for replacement by similar jaws of a larger or smaller size. The inner ends of the jaws 46 and 48 terminate in elongated cams 70 and 72 having inclined and arcuate outer peripheries 74. A coil spring 76 positioned between the said cams normally retains the bearing faces of the jaws 46 and 48 in a frictionally clamped position, as shown best in Figure 2 of the drawings.

Frictionally positioned in the lower end 12 of the shank 10, and frictionally bearing upon the pivot pin 58, is a support ring 78 that engages the lower end of a coil spring 78. This spring 78 urges a slidable cam actuating ring 80 nor-

mally against an annular shoulder 82 provided in the inner periphery of the shank adjacent end 12.

The outer ends of the jaws 46 and 48 terminate in substantially flat extensions 84 and 86 having knurled or roughened outer faces 88.

In practical use of the device, by rotating the shaft 24 in one direction, the same will move longitudinally in the shank 10, so that the member 44 will frictionally engage the ring 80 and force the same against the inclined, rounded surfaces of the cams, thus pivoting the outer ends of the jaws 46 and 48 outwardly, so that the knurled surface of the tips 84 and 86 will frictionally engage the kerf 90 provided in one end of a suitable fastener 92. In such a position, the handle 18 may be manipulated in a convenient manner so that the fastener may be inserted in openings otherwise difficult for an operator's hand to extend.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An expandible jaw screw-driver comprising a hollow shank open at its lower end, a handle fixed to the opposite end of said shank, a pair of companion jaws pivoted to the lower end of said shank, the outer ends of said jaws projecting outwardly from the lower end of said shank, cams carried by the inner ends of said jaws and positioned within the shank, a cam engaging ring slidably mounted within said shank and embracing the inner ends of said jaws for actuating said jaws to a spread position, means for normally retaining said jaws in a clamped position, means for selectively adjusting said cam actuating member within said shank, a support ring mounted in the lower end of said shank, and a spring member biased between said support ring and

said cam engaging ring to urge the cam engaging ring out of engagement with said cams.

2. An expandible screw-driver comprising a hollow shank open at its lower end, a pair of companion jaws having inner and outer end portions, means pivotally securing the jaws together intermediate their ends and also securing the jaws to the lower end of the shank, the outer end portions of the jaws projecting beyond the open end of the shank, a support ring mounted in the lower end of the shank and embracing the jaws, cams carried by the inner end portions of said jaws, a jaw actuating ring member embracing said cams, a coil spring embracing the inner end portions of said jaws and biased between said support ring and said jaw actuating ring member, a resilient member biased between the inner end portions of said jaws and urging the outer end portions of said jaws toward each other, and an adjustable member carried by said shank for forcing the jaw actuating ring member against the cams to urge the inner end portions of said jaws toward each other and to urge the outer end portions of said jaws apart.

25 3. The combination of claim 2 wherein said means pivotally securing the jaws together intermediate their ends and also securing the jaws to the lower end of the shank includes a pin extending through the jaws, said shank having an aperture adjacent its lower end receiving one end of said pin, and a key slot provided in the shank adjacent the lower end thereof and diametrically opposite from the aperture receiving the other end of said pin, said pin being removable from said aperture and said slot for removing the jaws from the lower end of said shank.

CHARLES O. MACLEAN.
